UNITED STATES PATENT OFFICE.

FRANK RATH, OF BINGHAMTON, NEW YORK, ASSIGNOR TO BUNDY MANUFACTURING COMPANY, A CORPORATION OF NEW YORK.

RESETTING MECHANISM FOR WHEELS.

No. 859,410.

Specification of Letters Patent.

Patented July 9, 1907.

Application filed February 2, 1905. Serial No. 243,882.

To all whom it may concern:

Be it known that I, FRANK RATH, a citizen of the United States, and a resident of Binghamton, county of Broome, State of New York, have invented new and useful Improvements in Resetting Mechanism for Indicating-Wheels, of which the following is a specification.

My invention relates to resetting mechanism for indicating wheels. In the accompanying drawings it is shown as embodied in an adding machine. While my invention is particularly applicable to such machines its use is not limited to them but is applicable to any machine in which it becomes necessary to reset wheels at a normal position after they have been moved therefrom.

The object of my invention is to provide simple and easily operated means for resetting wheels at their normal position, means that will be accurate and certain in operation and that cannot be easily deranged. In my improved devices the resetting mechanism is normally not in engagement with the devices it resets but at the proper time it is moved into the path of rotation of such parts or connections thereof and moved concentrically along said path.

In the drawings accompanying this specification and forming a part hereof I have shown the preferred form or embodiment of my invention. It is there shown in connection with the adding wheels of an adding machine. It is, however, not restricted to use in such machines but may be used in connection with any wheel or wheels that have to be reset to a normal or original position.

Referring to the specific form shown in the drawings Figure 1 is a side elevation of an adding machine containing my invention, a part of the side casing being broken away to show the handle and connections; Fig. 2 is a view of the same machine from the opposite side with a part of the casing similarly broken away; Figs. 3, 4 and 5 are diagrammatic views showing the reset mechanism in three different positions, and Fig. 6 is a rear view of the reset mechanism.

1 represents the case of an adding machine embodying my invention of which 2, 2 are the keys arranged in the ordinary manner. The machine shown is adapted to print upon any suitable recording surface the number represented by the keys depressed and also to add that number upon suitable adding wheels.

3 represents a type segment bearing type 4. The machine is equipped with one type segment for each series in the bank of keys although only one type segment and series of keys are shown in the drawings.

5, 5 are total adding wheels upon which the numbers represented by the keys depressed are added. The mechanism by which the keys operate the type

segments to bring the proper numbers upon the printing line form no part of this invention and are, therefore, not shown and described. Any suitable connecting mechanism may be employed for the purpose. The type segments 3 communicate their movement through segmental gears 6 forming part of segment 3 meshing with intermediate adding wheels 7 loosely mounted on shaft 8 and meshing with gear wheels 9 which are secured to total adding wheels 5. The total adding wheels 5 and their gears 9 are loosely mounted on shaft 10. In the form of machine shown in the drawings the type segments 6 are loosely mounted on a shaft 11 movably supported by two rocking arms 12, only one of which is shown in the drawings. These arms are fast upon rock shaft 13. After the keys 2 have been depressed the operator pulls forward the operating handle 14 which is then returned to place by any suitable means. The movement of this handle 14 operates the different parts of the machine causing the movement of the type segments in proportion to the value of their respective keys that have been depressed and performing the other acts required in the operation of the machine. As these form no part of the present invention none of them are shown and described. Among the said operations resulting from the movement of the operating handle 14 is the rocking of rock shaft 13 to the right as viewed in Fig. 2, bringing the gear 6 into mesh with the teeth of the adding wheels 7. This is arranged to take place on the very beginning of the operation of the machine and before the type segments 3 begin their retrograde or adding movement. The means for rocking shaft 13 form no part of the invention and are not shown in detail and will not be further described. The movement of the type segments 3 accordingly moves the adding wheels 7 in proportion to the value of the keys that have been depressed and this movement is transmitted to the total adding wheels 5. The different numbers thus represented by the different keys depressed in successive operations of the machine will be added during those operations upon the adding wheels 5, the number standing upon the reading or printing line of these wheels at any time representing the total of all of the additions up to that point. My improvement relates to the resetting of such adding wheels or similar devices at their original or zero positions. My resetting device is arranged to be normally out of the path of the adding wheel or other wheel and upon the commencement of the resetting operation it is first moved into such path and then circumferentially along the path.

Referring to the specific form shown in the drawings the resetting device consists of a series of reset levers 15, one for each adding wheel 7, loosely mounted on

a stud 16 fast to and carried by two arms 17 fast on rock shaft 18. Each reset lever 15 is provided with a slot 19 and through all of the slots passes a stud 20 fixed to the framework of the machine. 21, 21 are pins fixed to the side of each adding wheel 7 and spaced ten teeth apart. As shown these wheels 7 are provided with forty teeth. The end of each reset lever 15 is slightly hollowed out at 22 for engagement at the proper time with one of the pins 21.

10 Shaft 18 can be rocked in any suitable manner. As shown in the drawings it is rocked by means of a reset handle 23 fixed on shaft 24 on the outside of the casing of the machine as shown in Fig. 1. When handle 23 is rocked it rocks arm 17 to the left as shown in Fig. 2, 15 imparting a similar movement to reset levers 15. Cam 19 is so shaped as to throw the end of lever 15 first in an upward direction into the path of rotation of pins 21 and then to move the end of reset lever in a line concentric with the center of shaft 8, or in other words, 20 into the path of rotation of pins 21. In this movement it will encounter or pick up one of the pins 21 wherever it may be and will move it to its normal or zero position. Through this movement adding wheels 5 will be moved back to their zero position. This 25 double movement of lever 15 is caused by fixed pin 20 riding in the peculiarly shaped slot 19.

My improved resetting mechanism is simple in character, easily operated, accurate and certain in operation and is not liable to derangement. It will, 10 of course, be understood that modifications may be made from the specific form of devices shown in the drawings without departing from my invention.

My improvement has been devised in connection with the construction of the adding machine shown in part in the drawings, the rest of the machine, not 35 claimed herein, is not an invention of mine. My invention, however, is not limited to use in connection with such machines.

What I claim as new and desire to secure by Letters Patent is,—

1. The combination of a set of adding wheels, resetting pins, a resetting device for each wheel provided with a cam slot, a fixed common stud extending through all of the cam slots, and means for moving the resetting devices, the cam slots being so shaped and arranged that the resetting devices will normally be out of the paths of rotation of the resetting pins but will in their movement be moved by the cam slots first into such paths and then circumferentially along such paths to move the adding wheels to their zero positions.

2. The combination of an adding wheel, a resetting pin projecting from the side of the wheel, a movable resetting arm provided with a finger adapted, when in operative position, to engage the resetting pin, and also provided with a cam slot, a stud projecting through the cam slot, means for moving the resetting arm, the cam slot being so shaped and arranged that the finger of the resetting arm will normally be out of the path of rotation of the resetting pin, but, when the arm is moved by the cam slot, the finger will be moved first into the path of rotation of the resetting pin and then circumferentially along such path to move the adding wheel to its zero position.

In testimony whereof, I have signed my name to this specification, in the presence of two subscribing witnesses.

FRANK RATH.
